Primary Examiner — Karen E Kearney(74) *Attorney, Agent, or Firm* — NSIP Law(57) **CLAIM**

The ornamental design for a universal serial bus connector, as shown and described.

DESCRIPTION

FIG. 1 is a front perspective view of a universal serial bus connector showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

The broken line showings of the USB indicia and cable are included for the purpose of illustrating portions of the universal serial bus connector and form no part of the claimed design.

1 Claim, 5 Drawing Sheets(56)
